UNITED STATES PATENT OFFICE

119,265

DESIGN FOR A TOY VESSEL

Marie E. Hollman, Edgewater, Colorado

Application December 5, 1939, Serial No. 88,698

Term of patent 3½ years

To all whom it may concern:

Be it known that I, Marie E. Hollman, a citizen of the United States and resident of Edgewater, in the county of Jefferson and State of Colorado, have invented a new, original, and ornamental Design for a Toy Vessel, of which the following is a specification, reference being had to the accompanying drawing, forming part thereof.

In the drawing

I claim

The ornamental design for a toy vessel, as shown.

MARIE E. HOLLMAN.
